UNITED STATES PATENT OFFICE.

MAX SCHOLL, OF HOUSTON, TEXAS.

AUTOMATIC CIRCUIT MAKER AND BREAKER.

1,158,729.

Specification of Letters Patent.

Patented Nov. 3, 1915.

Application filed June 5, 1914. Serial No. 843,195.

To all whom it may concern:

Be it known that I, MAX SCHOLL, a subject of the Emperor of Austria-Hungary, residing at Houston, in the county of Harris and State of Texas, have invented certain new and useful Improvements in Automatic Circuit Makers and Breakers, of which the following is a specification.

This invention relates to new and useful improvements in an automatic circuit maker and breaker.

The object of the invention is to provide a device of the character described which includes a mechanism in connection with electrical conductors, whereby at stated intervals the circuit through said conductors is completed and likewise broken.

With the above and other objects in view the invention has particular relation to certain novel features of construction and operation, an example of which is given in this specification and illustrated in the accompanying drawings wherein—

Figure 1 is a side elevation of a clock with the improved device shown in connection therewith. Fig. 2 shows a rear view thereof. Figs. 3, 4 and 5 show detail views of detached parts of the device. Fig. 6 shows an end view of the part shown in Fig. 3, and Figs. 7 and 8 show side and end views respectively of a collar employed in the device.

Referring now more particularly to the drawings, wherein like numerals of reference designate similar parts in each of the figures, the numeral 1 refers to a clock of the ordinary and well known construction. Any form of chronometer, however, may be employed, as may be found most practical.

The numeral 2 designates the hour hand post of the clock which rotates with said hand, performing one rotation each hour. The rear side of the clock casing has an orifice 3 alined with the post 2 and a cylindrical block 4, of non-conducting material fits in said orifice and is secured on the rear end of said post and fixed to the block 4 and projecting outwardly therefrom is the stud 5, square in cross section. A stub shaft 6 is provided whose inner end has a socket 6', square in cross sectional view and in which the stud 5 fits, the inner end of said shaft being split forming jaws which have a certain amount of flexibility, causing them to grip said stud. The shaft 6, in the main, is of uniform diameter but has an enlarged section 7 beyond which is the blank neck 8.

This shaft is formed of brass or some other good conductor and surrounding the blank neck 8 is the collar 9 which is rotatable independent of the shaft, and is formed of brass or some other good conductor and is in constant contact with the shaft 6. Threaded over the outer end of the shaft 6 and abutting against the section 7 is a sleeve 10 formed of non-conducting material and the extreme outer end of the shaft carries the sleeve 11 formed of conducting material. The section 7 and the sleeves 10 and 11 are of uniform diameter and are exteriorly threaded from end to end, the thread of each of these parts forming a continuation of the thread of the adjacent part. As shown in Fig. 1 there are two end sections formed of conducting material and an intermediate section formed of non-conducting material, but it is obvious that the number and relative lengths of these sections may be varied as desired.

Fixed to the clock 1 at some desirable place is a cylindrical casing 12 which surrounds a coil spring 13. One end of the casing has a bearing in which a short shaft 14 fits. The inner end of this shaft is secured to one end of the pull spring 13 and the other end of said spring is secured to the opposite end of the casing 12. One end of a rod 15 is pivoted to the outer end of the shaft 14 and the other end of this rod is formed into a hook 16, the free end of the hook being flattened and formed into a blade 90 whose edge rests between the threads of the section 7 and the sleeves 10 and 11. The hook 16 is separated from the rod 15 by means of a non-conducting section 17. This rod rests against the adjacent end of the casing 13 as a fulcrum and the pull of the spring 13 holds the hook 16 yieldably in contact with the parts carried by the shaft 6, it is apparent that the hook will travel in an arc and consequently the rod 15 should be elbowed out, as shown in Fig. 1, a sufficient distance to remain in contact with the parts 7, 10 and 11, throughout their entire length.

This device is designed particularly for the purpose of automatically cutting off the current to electric lights at regular intervals and also for automatically completing the circuit to said lights at the proper time. The circuit is completed to the light through the wire 18, collar 9, section 7, hook 16 and wire 19. It is obvious that the shaft 6 per-

forms a complete rotation each hour and as it rotates the hook 16 will move along toward the end thereof. The number of turns of the thread of section 7 will fix the number of hours required for the hook 16 to reach the non-conducting section 10. When this section has been reached the circuit will be broken and the lights on said circuit will go out. The hook 16 will continue to move 10 along the sleeve 10 approaching the sleeve 11. When said sleeve 11 is touched by said hook the circuit will be again completed through the lights. It is obvious that the times may be accurately fixed when the circuit will be completed and broken, the same being determined by the number of threads carried by the conducting and non-conducting sections of the shaft 6, when the hook 16, reaches the outer end of section 11, it may 20 then be manually replaced at the starting point.

The block 4 and the section 17, both of non-conducting material, insulate the clock from the electrical current and the movement of said clock is not affected by said current.

What I claim is:—

1. A device of the character described, including an operative mechanism, a threaded shaft in operative connection therewith and rotated thereby, a movable member in yieldable contact with the threads of said shaft and moved thereby along said shaft, a casing fixed to said mechanism, a pull-spring 30

mounted therein, one end of which is attached to the casing and the other end of 35 which is connected to one end of said movable member and by means of which said member is held in yieldable contact with said threads, an electrical current conductor in constant contact with said shaft and an electrical conductor in constant contact with 40 said movable member.

2. A device of the character described including an operative mechanism, a threaded shaft in operative connection with and rotated by said mechanism, a movable member 45 in yieldable contact with the threads of said shaft and moved thereby along the shaft, a resilient member in operative connection with one end of said movable member and 50 by means of which said member is held in yieldable contact with said threads, a suitable casing fixed to said mechanism and enclosing said resilient member, an electrical current conductor in constant contact with 55 said shaft, and an electrical current conductor, in constant contact with said movable member.

In testimony whereof I have signed my name to this specification in the presence of 60 two subscribing witnesses.

MAX SCHOLL.
